ELECTRIC FILTER

Dana H. Bacon, Arlington, Mass., assignor to
National Company, Inc., Malden, Mass., a cor-
poration of Massachusetts

Application January 25, 1939, Serial No. 252,794

9 Claims. (Cl. 178—44)

This invention relates to electric wave filters and particularly to crystal filters adapted to admit a frequency band of predetermined width and reject a predetermined frequency whose location with respect to the admitted fundamental frequency may be varied within wide limits. The invention finds great utility in the field of communications although it is to be understood that its use is not limited thereto.

10 As one example of the use of my invention is cited radio receivers operating in high carrier frequency ranges such as in the amateur bands in the United States. In such receivers, a wave band of about 100 cycles is ample for signaling purposes. This has resulted in extremely close (in comparison to the carrier frequency) spacing between channels.

Obviously microscopic channel spacing requires extreme selectivity. In addition, it frequently becomes necessary to eliminate an interfering signal of unusual power as compared to the general signal background, which interfering signal may be but 100 or 200 cycles away from the desired fundamental signal frequency.

25 In order to meet this situation, the crystal filter described in United States Patent No. 2,054,757 to Lamb was devised. In this filter, means are provided for moving the anti-resonant peak of the crystal above or below its resonant frequency. This type of filter is used in an intermediate frequency stage of a superheterodyne circuit.

Thus in Fig. 3 of this patent, the crystal filter is shown both as a selectivity control filter, i. e., band width control, and also as a rejection filter. These two functions should be independent but in the Lamb system this is not the case. An interlocking between the two is found. When one control is exercised it tends to throw off the previous adjustment of the other control. This is particularly objectionable at high frequencies of the order of 1500 kilocycles. The difficulty resides in the fact that the capacitance of the rejection part of the filter is effectively in parallel with the capacitance of the selectivity portion of the filter. Since these capacitances are additive, it is evident that a variation of either one causes the total to vary and thus result in both controls having a functional interlocking.

50 In order to eliminate this interlocking of both

variables this invention was devised. Not only have I eliminated the interlocking between the band width control and the rejection frequency control, but in addition I have found that a quicker and more flexible operation of the rejection control results. By my invention, the rejection frequency may be moved from any predetermined value on either side of the admitted fundamental frequency smoothly up to and as close to the fundamental as may be desired, the approach being asymptotical in nature. The resulting filter maintains a constant impedance looking in so that no reflections or reactions are possible on the feeding circuit.

In general I accomplish the above by associating with the rejection control condenser a second condenser across the crystal and electrically coupling the two condensers in a manner to maintain a substantially constant capacity across the input terminals of the filter.

The filter is of general application and may be used for all frequency bands.

Referring to the drawings, Fig. 1 shows a circuit diagram of the filter; Fig. 1A is a modification; Fig. 2 shows curves indicating the relationship between phasing condenser adjustment and rejected frequency; Fig. 3 is a circuit in which the filter may be used; Fig. 4 shows the filter characteristics; Figs. 5, 6 and 7 are curves for a specific phasing condenser.

Referring to Fig. 1, input lines 10 and 11 are connected to filter input terminals 12 and 13. These terminals are adapted to be supplied with alternating currents of different frequencies and forming a band such as might be found in a modulated carrier. It is understood, of course, that any number of frequencies may be supplied since the filter attenuates those frequencies outside of the band which it is adapted to pass.

Between input terminals 12 and 13 are four arms 15, 16, 17 and 18 of a filter bridge. At the junction of arms 15, 16 and 17, 18 respectively, there are output terminals 20 and 21 connected to an output circuit 22 and 22'. In arms 15 and 16 are variable condensers 23 and 24 adapted to be operated by one control. The two condensers 23 and 24 may really be considered as a single condenser split up into two series connected sections. Across the two condensers is connected a suitable inductance 25. Under certain conditions

this inductance may be omitted as a discrete element and reliance had upon the inductance of associated elements.

Arm 17 contains a phasing condenser section composed of a stator 27 and rotor 28. Arm 18 contains the rest of the phasing condenser composed of a stator 29 also cooperating with rotor 28. Physically, condensers 27-28 and 28-29 may be separate. The only requirement is that the series capacitance 27-28 and 28-29 remain constant over the operating range of the filter. This may be accomplished in various ways. Thus two condensers may have a suitably shaped cam drive to provide the displacement for satisfying this requirement. It is also possible to cut the plates of a variable condenser to a formula to satisfy this condition. This will be elaborated later.

Arm 17 has in shunt to condenser 27-28, a piezo-crystal 31 in a suitable holder. This crystal is cut to resonate at the desired fundamental admitted frequency of the filter. Arm 18 has a variable resistance 33 in shunt to condenser 28-29.

Looking from one input terminal toward the other input terminal, it is clear that the reactance of the filter will be determined by the setting of condensers 23 and 24. Since phasing condensers 27-28-29 have a constant capacity, it follows that the band width controlled by condensers 22-23 will not be altered by an adjustment of the phasing condensers. The crystal itself will behave like an extremely sharply tuned circuit.

Upon adjustment of phasing condensers 27-28-29, the phase of currents going along arm 17 to output junction 21 will be varied with respect to currents going along arm 18. In other words, the balance of the bridge for output purposes is shifted. In this way, the rejected frequency going along arms 17 and 18 toward point 21 cancels out. It is clear that as the balance is shifted, the anti-resonant characteristics of the opposing arms 17 and 18 change. This is evident if we consider the reactance of the system between output points 20 and 21. In that case 17 plus 15 and 18 plus 16 each have different reactances as phasing condensers 27-28-29 are adjusted.

In order to compensate for variations in power factor of crystal 31 at different frequencies variable resistance 33 is used. This resistance may be varied with change in phasing condensers 27-28-29 to maintain the power factor of the filter uniform.

The variation is such that when the phasing condensers are at their extreme positions; i. e., one section at a maximum value and the other section at a minimum value to provide extreme bridge unbalance, the resistance is at a minimum value. The resistance then varies to its maximum value as the phasing condensers are adjusted to balance the bridge and, of course, goes to its minimum value as the bridge unbalances in the reverse manner. The exact value of the resistance is a function of the crystal characteristics, particularly its Q. Thus for crystals operating in the neighborhood of 1500 kilocycles, resistance 33 may vary from 50,000 ohms to 250,000 ohms.

The precise values and the variation characteristics, however, may be determined by simple experiment and the above values are merely given for illustrative purposes. In fact, resistance 33 may be fixed at some suitable value intermediate 75 the normal maximum and minimum with gain in

control simplicity and no great sacrifice of efficiency.

In Fig. 1A, a modification is shown wherein resistance 33', for compensation of power factor variation in the crystal, is disposed directly in series with section 28-29 of the phasing condenser. The resistance is at its maximum value at extreme bridge unbalance and varies down to its minimum value upon bridge balance. The resistance in such case may vary from a few ohms up to about 500 ohms. Or a fixed resistance of some suitable intermediate value may be used.

Referring to condensers 27-28-29, the condition is that the series capacitance in arms 17 and 18 of the bridge be maintained at a substantially constant value in spite of adjustments. It is clear that the capacity of the crystal portion of the circuit is added to that of section 27-28 of the phasing condenser.

From a mechanical angle, the simplest solution to a design of condensers 27-28-29 is to use conventional gang variable air condensers such as are used in radio receiving sets but shape the plates in such a manner that the constant series capacitance relation will hold.

Let us assume that C_1 and C_2 are two variable capacitances under consideration. Let M and N be the minimum values for C_1 and C_2 respectively.

As applied here, the minimum value would include the crystal capacitance as well.

Then

$$\frac{1}{C_1 + M} + \frac{1}{C_2 + N} = \frac{1}{K}$$

It should be clearly understood that C_1 and C_2 represent the variable portion in the equation so that either one of these can vanish. Let us assume that C_1 and C_2 each vary from zero to maximum values C_1' and C_2' respectively. It is obvious that as one of these variables increases, the other decreases. Hence, when C_1 is a maximum

$$\frac{1}{C_1' + M} + \frac{1}{N} = \frac{1}{K} \quad (1)$$

Also, when C_2 is a maximum

$$\frac{1}{M} + \frac{1}{C_2' + N} = \frac{1}{K} \quad (2)$$

Solving Equation 1 for N , we have

$$N = \frac{C_1' K + K M}{M + C_1' - K} \quad (3) \quad 50$$

Solving Equation 2 for N , we have

$$N = \frac{C_2' K + K M - M C_2'}{M - K} \quad (4) \quad 55$$

It follows, therefore, that Equations 3 and 4 are equal to each other.

$$N = \frac{C_1' K + K M}{M + C_1' - K} = \frac{C_2' K + K M - M C_2'}{M - K} \quad (5) \quad 60$$

For the sake of brevity let

$$\frac{C_1' K + K M}{M + C_1' - K} = X$$

and

$$\frac{C_2' K + K M - M C_2'}{M - K} = Y \quad 65$$

Then $N = X = Y$.

In the above equations, K is a constant whose value is a function of the maximum and minimum capacitances of the phasing condensers and may be a known arbitrary quantity. Similarly, C_1' and C_2' represent arbitrary values whose magnitudes, like that of K , is dependent upon the general circuit constants. Hence, 70 75

$X=Y$ can be solved for M if K has a fixed value or can be solved for K if M has a fixed value. Then from $N=X=Y$ the value of N can be determined.

5 Referring back to the basic equation

$$\frac{1}{C_1+M} + \frac{1}{C_2+N} = \frac{1}{K}$$

and solving respectively for C_1 and C_2 , we have

$$10 C_1 = \frac{KC_2 + KN + KM - C_2 M - MN}{C_2 + N - K} \quad (6)$$

and

$$15 C_2 = \frac{KC_1 + KM + KN - C_1 N - MN}{C_1 + M - K} \quad (7)$$

By assigning various values to C_1 (or C_2), and solving the corresponding equation above, a curve may be drawn showing how C_1+M varies with respect to C_2+N .

20 The final solution involves the variation of the expression

$$\frac{C_1+M}{C_2+N}$$

25 with respect to rotation of condenser shaft. This ratio may vary between the two limits

$$25 C_1' + M \quad (8)$$

and

$$30 \frac{M}{C_2' + N} \quad (9)$$

as C_1 and C_2 respectively attain maximum values.

From the above equations and C_1+M and C_2+N curves, it is possible to plot one curve involving

$$\frac{C_1+M}{C_2+N}$$

40 and C_2 as the two variables. Since the manner in which ratio

$$\frac{C_1+M}{C_2+N}$$

45 varies with angular rotation of condenser shaft is known, the curves of capacity against rotation for C_1 and C_2 may be determined directly from the above mentioned curves.

In particular, for high frequency work it is desirable to reduce the fixed capacitances, such as crystal mounting and minimum capacity of variable condenser to as low a value as possible since the minimum values determine how closely the anti-resonant peak can approach the fundamental frequency. This is illustrated in Fig. 2 showing phasing condenser adjustment plotted against 55 the anti-resonant frequency.

The vertical axis indicates an extreme phasing condenser setting. Thus the point marked C_1 may indicate the maximum capacity for one section of the phasing condenser and minimum 60 for the other while C_2 may indicate the reverse condition; i. e. the phasing condenser at the other end of its range. The horizontal axis indicates the rejected frequency with the crystal resonant frequency as at the origin. It will be 65 observed that the greater the phasing condenser unbalance, the nearer the rejected frequency will approach the crystal resonant frequency. Obviously, this gap can never be eliminated. But by reducing minimum capacities, as pointed out before, the approach of the rejected frequency to the crystal frequency can be made exceedingly close, of the order of 100 cycles to a crystal frequency of 1500 kilocycles, about .007%.

70 From the previous equations, it will be noted that the maximum values C_1' and C_2' need not

necessarily be equal. In other words, the rejection curves need not necessarily approach the crystal frequency with the same curvature nor need they terminate at the same distance from the crystal frequency. Thus on one side, the rejection frequency may come up to 100 cycles away from the crystal frequency, while on the other side it may come closer to or end further away. The condenser plates are not necessarily of the same shape.

5 The filter may be disposed in a suitable amplifier stage and, as pointed out, is adapted to be used in a receiver. For convenience, it is shown in the intermediate stage of a superheterodyne circuit. It is obvious, however, that the filter 15 may be used in any system and may be applied to cover any desired frequency band.

Thus in Fig. 3, a transformer 50 is supplied with intermediate frequency currents of 1500 kilocycles, or any other desired frequency. It is 20 understood, of course, that this intermediate frequency has added or subtracted thereto the modulating frequency. Transformer 50 has a secondary 51 which is shunted by a variable condenser 52. This condenser 52 is adapted to control the band width. Across condenser 52 are two series condensers 53 and 54 of fixed capacity. Obviously, condensers 52, 53 and 54 must all be treated as a lump capacity with regard to band width control. A ground 55 is taken at the junction of condensers 53 and 54 and this ground is one output terminal of the filter. Points 56 and 57 may be considered as the input terminals of the filter.

From point 56 a piezo-crystal element 58 extends to the other output terminal 60. In parallel to the crystal is a variable condenser having opposing electrodes 61 and 62. From point 57 to point 60 is a variable condenser having electrode 63 cooperating with electrode 62. As will 40 be understood, condensers 61, 62 and 63 operate in a manner to maintain a substantially constant series capacitance between points 56 and 57 through these two arms only. The relative proportions of these capacitances vary of course. 45 Across condenser 62-63 is a resistance 65 which may be variable if desired. In practice, however, the variation of resistance 65 for amateur reception is not important and satisfactory results are secured with a fixed resistance.

50 As condensers 61-62-63 are varied, the power factor of crystal 58 varies with change in frequency to which these two arms are anti-resonant. Hence, the power factor across condenser 62-63 should vary similarly to maintain the 55 bridge balance. In the absence of such power factor balance, the rejection peak amplitude is smaller than is possible with this filter.

The output of the bridge may conveniently be fed through a coupling condenser 67. The condenser 67 leads to a coil 68 and thence may be handled in conventional manners. Condenser 67 and coil 68 together form an output load. Preferably this load should not be too large in comparison to the bridge impedance range since the 65 rejection characteristics will be undesirably affected.

In Fig. 4 are curves showing the characteristics of the filter. Curve A shows the transmission efficiency of various frequencies through the 70 bridge filter with the rejected frequency outside of the band. By manipulating condenser 52 or adjusting the capacitance due to condensers 52, 53 and 54, the width of the band may be controlled. The minimum width is naturally the 75

resonant frequency of the crystal and is only a theoretical possibility as the capacities and resistances in the bridge approach zero. Curve B shows the effect of the rejection control operating within the band limits. The crystal curve itself is extremely sharp as is well known. Since this rejection curve is never symmetrical with respect to the bridge resonance curve, curve B will always have a non-symmetrical outline. The height of the rejection curve is a function of the power factor of the crystal and adjacent phasing condenser arm.

The interposition of resistance 65 tends to balance the losses in both bridge arms and results in a higher rejection curve amplitude. In other words, the rejection is more perfect.

It is to be understood, of course, that the various constants and ranges of variables will be different for different frequency bands. Furthermore, even for the same filter, the shapes of the two phasing condensers have an infinite variation. Either section of the phasing condenser may be taken as a standard and as a result may be endowed with definite capacity change characteristics and this will determine the other section characteristics and shape in accordance with the equations previously given. As a specific example, a filter for handling a fundamental frequency of 1560 kilocycles with a modulating frequency range of about 7000 cycles is herewith described.

From well-known bridge equations, it may be determined that the desired phasing range will result with a maximum capacitance variation of 50 micromicrofarads, hereinafter abbreviated to mmf. Thus $C_1' = C_2' = 50$ mmf. The series capacity K of the two phase condenser bridge arms may be chosen to fit circuit conditions and for the frequency of 1560 kilocycles may advantageously be taken as 10 mmf. Then from Equation 5 we obtain the following:

$$\frac{50 \times 10 + 10M}{M + 50 - 10} = \frac{50 \times 10 + 10M - 50M}{M - 10}$$

$$45 \quad \frac{500 + 10M}{M + 40} = \frac{500 - 40M}{M - 10}$$

Solving for M, we obtain $M = 11.92$ mmf.

Also from the same Equation 5

$$50 \quad N = \frac{C_1' K + K M}{M + C_1' - K}$$

and substituting proper values for K, M, and C_1' , we obtain $N = 11.92$ mmf.

55 Here N is numerically equal to M. The condenser plates for both phasing sections need not necessarily be of the same shape.

Referring to Expressions 8 and 9,

$$60 \quad \frac{C_1' + M}{N} = 5.194$$

and

$$\frac{M}{C_2' + N} = .1925$$

65 By plotting the logarithm of the expression

$$\frac{C_1 + M}{C_2 + N}$$

against degree rotation of the gang condenser shaft, the phasing curve, as in Fig. 2, will be essentially symmetrical. This curve, Fig. 5, is a straight line. It may be any other shape, if desired.

Referring back to Equation 7, it will be necessary to assign various arbitrary values to C_1 be-

tween its limits and calculate the resulting values for C_2 .

C_1	C_2
0	50
1	32.33
2	23.60
4	14.96
8	8.16
16	3.60
32	1.03
50	0

5

10

It is now possible to plot $C_1 + M$ against $C_2 + N$, shown in Fig. 7, although the curve itself is not necessary. It is interesting to note how one varies with the other.

$C_1 + M$	$C_2 + N$
11.92	61.92
12.92	44.25
13.92	35.52
15.92	26.88
19.92	20.08
27.92	15.52
43.92	12.95
61.92	11.92

20

25

To actually determine the capacity curves A' and B', a new table of

$$\frac{C_1 + M}{C_2 + N}$$

is made corresponding to the changes in C_1 and C_2 given above.

$\frac{C_1 + M}{C_2 + N}$
.1925
.2920
.3919
.5922
.9920
1.792
3.392
5.194

35

40

Going to the curve of Fig. 5, we find the percent rotation of the condenser corresponding to the above values. Thus we know that the full condenser range or 100% corresponds to .1925.

We may, therefore, make up the following table:

$\frac{C_1 + M}{C_2 + N}$	Percentage rotation	C_1	C_2
.1925	100	0	50
.2920	87.2	1	32.33
.3919	78	2	23.6
.5922	65.2	4	14.96
.9920	50.1	8	8.16
1.792	32.4	16	3.60
3.392	13.2	32	1.03
5.194	0	50	0

50

60

Fig. 6 shows two curves. Curve A₁ shows the variation of C_1 against percent shaft rotation (a logarithmic function of

$$\frac{C_1 + M}{C_2 + N}$$

65

Curve B₁ shows C_2 plotted against percent shaft rotation. It is understood, of course, that 100% shaft rotation means the entire range and may, for example, be 180° customary in gang condensers. Different angular ranges may be used as desired. From these curves the actual fabrication of condenser plates (or drive cams) may be made.

Since the capacity of an ordinary variable air

70

75

condenser is a direct function of the opposed electrode areas, it is merely necessary to find the shape of plate which yields the desired capacity C_1 or C_2 , as the case may be, for a definite rotation of the shaft. Each capacity increment dC is equal to $\frac{1}{2} R^2 dG$, an increment of area where R is the radius vector and dG is the rotational angular increment of one electrode plate. Since dG is known and since the expression $dC = \frac{1}{2} R^2 dG$ is known, it is obvious that R may be determined for each condenser increment. In the above example, the figures are accurate for commercial purposes. Referring now to Fig. 3, the circuit constants for a 1560 kilocycle bridge are given.

Part No.	Constant
51	microhenrys
52	micromicrofarads
53	do
54	do
67	do
68	microhenrys
69	micromicrofarads
65	ohms
	80
	5-50
	140
	140
	10
	80
	10-100
	50,000-250,000

The input coil for 51 may have an inductance of 80 microhenrys and is closely coupled thereto. The crystal, of course, has a resonant frequency of 1560 kilocycles.

Fig. 7 shows the capacity relationship between phasing condenser sections where K is 10 mmf. In this curve C_1+M is plotted against C_2+N . Because of the constants chosen, the curve is more or less symmetrical. However, this is not always true.

What is claimed is:

1. An electric wave filter of variable pass-band width having a piezo-crystal element for determining the minimum width of the frequency band passed by the filter, means for increasing the width of the band over a substantial range and means for suppressing a selected frequency, said two last named means being independent of each other whereby an adjustment of one means has substantially no effect on the operation of the other means.

2. A bridge type electric wave filter having a piezo-crystal in one arm for determining the minimum extent of the frequency spectrum passed by said filter, reactances including capacitors in the arms of said bridge, an input circuit connected across two bridge points, an output circuit connected across the other two points, means for varying the reactance of two crystal free arms in series across the input points to vary the width of the band passed by said bridge and means for varying the reactance of each of the remaining two arms in a manner to maintain the total series reactance thereof constant to suppress any selected frequency except the resonant frequency of the crystal, said two means being independently variable and without substantial effect on each other's operation.

3. A bridge type electric wave filter having a piezo-crystal in one arm for determining the minimum extent of the admitted frequency spectrum, reactances including capacitors in the arms of said bridge, an input circuit connected across two bridge points, an output circuit connected across the remaining two bridge points, means for varying the reactance of two crystal free arms in series across the input to vary the width of the band passed, and means for varying the capacitive reactance of each of the remaining two arms in a manner to maintain the total series capaci-

tance thereof substantially constant to suppress any selected frequency except the resonant frequency of the crystal, said two means being independently variable and without substantial effect on each other's operation.

4. A bridge type electric wave filter comprising four arms, an input circuit connected to two points and an output circuit connected to the remaining two points, reactances including capacitors in each arm, a piezo-crystal in one arm in parallel to the capacitor to determine the minimum width of the frequency spectrum passed, means for varying the reactance of two crystal free arms in series across the input to adjust the width of the band, and means for varying the relative proportions of reactance in the remaining two arms while maintaining the series reactance substantially constant to suppress any desired frequency except the resonant frequency of the crystal, said two means being independently variable and without substantial effect on each other's operation.

5. The bridge filter of claim 4, wherein said reactance varying means in the remaining arms comprises a pair of variable condensers having the characteristic of varying the relative capacitances of each of these two arms while maintaining at a substantially constant value the series capacitances thereof.

6. The filter system of claim 4, wherein a resistor is connected across the capacitor in series with the crystal containing arm to compensate for varying power factors in the crystal at various frequencies.

7. A bridge type of electric wave filter comprising an input circuit, a pair of bridge arms in series across said input circuit, said arms having inductive and capacitative reactance with the junction of said arms forming an output terminal, two additional arms in series across the input circuit with their junction forming an output terminal, a crystal in one of said additional arms, a predominantly capacitative reactive element in the other additional arm, a reactance element connected across said crystal and means for varying the reactance of each of said additional arms with respect to each other while maintaining the series reactance of said additional arms substantially constant, said means being independent of each other and having no substantial effect on the operation of each other.

8. A bridge type electric wave filter having a piezo-crystal in one arm for determining the minimum extent of the admitted frequency spectrum, reactances including capacitors in the arms of said bridge, an input circuit connected across two bridge points, an output circuit connected across the remaining two bridge points, means for varying the reactances of two crystal free arms in series across the input to vary the width of the band passed, means for varying the capacitative reactance of each of the remaining two arms in a manner to maintain the total series capacitance thereof substantially constant to suppress any selected frequency except the resonant frequency of the crystal, said two means being independently variable and without substantial effect on each other's operation and a resistance in series with the capacitative reactance in that one of the remaining two arms which is free of crystal, said resistance being adapted to compensate for power factor losses present in the crystal.

9. In combination, a two-section series connected gang condenser, each section having means for varying the capacitance thereof be-

tween fixed limits, and means for simultaneously varying the capacitance of each section in an opposite sense in accordance with the following equations:

$$5 \quad C_1 = \frac{KC_1 + KN + KM - C_1 M - MN}{C_1 + N - K}$$

$$C_2 = \frac{KC_1 + KM + KN - C_1 N - MN}{C_1 + M - K}$$

and

$$\frac{C'_1 K + KM}{M + C'_1 - K} = \frac{C'_2 K + KM - MC'_2}{M - K}$$

where the letters represent the quantities set forth in the specification.
